UNITED STATES PATENT OFFICE.

THOMAS BURNS, OF WASHINGTON, DISTRICT OF COLUMBIA.

NECKTIE-FORM.

1,051,678.

Specification of Letters Patent. Patented Jan. 28, 1913.

Application filed September 9, 1912. Serial No. 719,420.

To all whom it may concern:

Be it known that I, THOMAS BURNS, a citizen of the United States, residing at Washington, in the District of Columbia, have invented certain new and useful Improvements in Necktie-Forms; and I do hereby declare the following to be a full, clear, and exact description of the invention, such as will enable others skilled in the art to which 10 it appertains to make and use the same.

This invention relates to neck tie forms and has for an object to provide an extremely simple and inexpensive necktie form which will have novel attaching means for 15 adjustably securing the neck tie high or low in the neck tie space of a collar.

With the above objects in view the invention consists of the novel details of construction and combination of parts hereinafter 20 fully described and claimed, it being understood that various modifications may be made within the scope of the appended claims.

In the accompanying drawing forming 25 part of this specification, Figure 1 is a front elevation of my invention applied. Fig. 2 is a longitudinal sectional view taken on the line 2—2 Fig. 1 with the tie removed. Fig. 3 is a view similar to Fig. 2 with the form 30 in position to dispose the tie high in the tie space of the collar. Fig. 4 is a detail perspective view of the tie form.

Referring now to the drawing in which like characters of reference designate similar parts, 10 designates a collar and 11 an ordinary neck tie tied in a four in hand knot 35 on my improved neck tie form 12.

The neck tie form comprising the subject matter of this invention consists of a single 40 substantially T shaped blank of material, and an inverted U shaped pin adapted to hook over a collar button and adjustably passed longitudinally through spaced openings in the shank of said blank with a resultant bight in said shank causing the edges of said openings to frictionally engage and hold said pin in adjusted positions.

For adjustably securing the tie form high 45 or low in the neck tie space of the collar, there are two pairs of openings 13 and 14 formed in the shank 15 of the form. A single inverted U shaped wire pin 16 of about 50 the size and stiffness of an ordinary un-

crimped hair pin is passed downwardly through both pairs of openings with both ends extending along the rear face, and the intermediate portion extending along the front face of the form shank. 55

The neck tie is knotted on the form in the usual and well known manner and exposes the bight of the pin 16 on the rear face of the form. To attach the neck tie the bight of the pin is hooked over the collar button 60 17. Should it be desired to wear the tie low in the tie space as shown in Fig. 1 the pin is pushed bodily upward and disposes the head 18 of the tie form upon the collar button as shown in Fig. 2. Should it be desired to 65 wear the tie high in the tie space the pin is pulled bodily downward and disposes the head of the form considerably above the collar button as shown in Fig. 3.

In any particular adjusted position of the 70 pin the bight 19 in the shank of the form made by inserting the pin through the openings, causes the edges of the openings to frictionally engage the pin and maintain the same against accidental movement. 75

What is claimed is:

1. A neck tie form comprising a substantially T shaped blank of material, and a pin adapted to engage a collar button and adjustably passed longitudinally through 80 spaced openings in the shank of said blank with a resultant bight in said shank causing the edges of said openings to frictionally engage and hold said pin in adjusted positions. 85

2. A neck tie form comprising a substantially T shaped blank of material, and an inverted U shaped pin adapted to hook over a collar button and adjustably passed longitudinally through spaced openings in the 90 shank of said blank with a resultant bight in said shank holding said pin in adjusted positions.

In testimony whereof, I affix my signature, in the presence of two witnesses.

THOMAS BURNS.
